UNITED STATES PATENT OFFICE.

NORMAN M. HENCH, OF WILKINSBURG, PENNSYLVANIA.

RAIL JOINT.

Application filed August 28, 1925. Serial No. 53,065.

This invention relates to the construction of rail joints or splice bars, and has for its object the provision of a novel form of splice bar having an I-beam distribution of metal, and having its central portion thickened or reinforced to better withstand the strain where the track rails are joined.

Another object is to provide a bar of this class of a novel design whereby the thickened or reinforced portion is on the inner face of the web only so that the same length bolts may be used throughout the joint.

A further object is to provide a bar of this class in which the metal is distributed so as to give the greatest strength.

A further object is to provide a bar of this class that may readily be rolled in a standard rolling mill, and due to its shape will not require the frequent and expensive dressing of the rolls such as is necessary with the bars of this class now used in the art.

A still further object is to provide a bar of the class described having the novel design, construction and combination of parts hereinafter described and illustrated in the accompanying drawings.

In the drawings—

Figure 1 is an end elevation showing my improved rail joint or splice bar as used on a railway track.

Figure 2 is a plan showing the web of my improved splice bar in longitudinal section.

Figure 3 is a similar sectional plan showing the contour of the web of a modified form of splice bar.

Figure 4 is a sectional plan, similar to Figures 2 and 3, showing a further modification in the outline of the web of the splice bar.

Referring more particularly to the drawings, the numeral 2 designates the abutting track rails which are connected or joined by the rail joint or splice bars A of this invention and bolts 3.

The bars A are formed of a rolled metal shape similar to the standard I-beam, that is, they have an I-beam distribution of metal and comprise a bearing head portion 4, web portion 5 and base flange portion 6.

The head portion 4 is adapted to engage the underside of the rail heads, and the base flange 6 is adapted to overlie the inclined top surfaces of the track rail flanges.

The web 5 extends perpendicular from a point intermediate the longitudinal edges of

the head 4 to a point intermediate the longitudinal edges of the base flange 6, and is of materially less thickness than either the head or base flange.

The web 5 is thickest at its center, as at 8, and tapers either gradually, as shown in Figures 1, 2 and 3 or in steps as shown in Figure 4 toward both ends. It will be especially noted that the outside face of the web is straight and that all the variation in thickness is on the inside face of the web, so that the same length bolts may be used throughout the rail joint.

The formation of the reinforcing or thickened web portion by gradually increasing its thickness along one side face eliminates the necessity of forming deep pockets in the rolls for die rolling and, therefore, eliminates the necessity for constant and expensive roll dressing as is necessary when rolling bars having abrupt changes in cross section.

The size and shape of the bars A are such that they will be spaced an appreciable distance from the web of the track rails, that is, the head 4 and base flange 6 will wedge against the under side of the rail heads and the inclined top of the rail flange, respectively, so as to prevent the inner face of the web of the splice bar from extending inwardly beyond the plane of the side face of the rail head, thereby forming a large open space 10 between the rail web and the splice bar web through which rail bonds may be freely passed, and furthermore, due to the novel design of the present splice bar the strains from the track rails will be better distributed through the splice bar when it is thus positioned.

While I have shown and described certain specific embodiments of my invention, it will be understood that I do not wish to be limited thereto since various modifications may be made without departing from the scope of my invention as defined in the appended claims.

I claim—

1. The combination with two abutting track rails of a rolled metal splice bar having an I-beam distribution of metal over its entire length, including a relatively thin web, said web having a flat outer face and having its inner face tapered longitudinally from its center toward each end, said bar being so proportioned that the inner face of its web at the middle of its length is

substantially in alignment with the plane of the side face of the rail heads, and the inner face of the web at its ends is materially outside of the plane of the side face of the rail heads.

2. The combination with two abutting track rails of a rolled metal splice bar having an I-beam distribution of metal over its entire length, including a relatively thin web as compared with the head and base flanges of said splice bar, said web having a flat outer face and having its inner face constantly tapered longitudinally over its entire width from its center toward each

end of the bar, said bar being so proportioned that the inner face of said web at the middle of its length is substantially in alignment with the plane of the side face of the rail heads, and the inner face of the web at its ends is materially outside of the plane of the side face of the rail heads, so that the entire web and the major portion of the entire splice bar is located entirely outside of the plane of the side of the rail heads.

In testimony whereof, I have hereunto set my hand.

NORMAN M. HENCH.
